UNITED STATES PATENT OFFICE.

HOLMES MARSHALL, OF PLAINFIELD, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,285,297.

Specification of Letters Patent. Patented Nov. 19, 1918.

Application filed June 29, 1912. Serial No. 706,591.

To all whom it may concern:

Be it known that I, HOLMES MARSHALL, a citizen of the United States, residing in Plainfield, in the county of Union and State of New Jersey, have invented certain new and useful Improvements in Combined Type-Writing and Computing Machines, of which the following is a specification.

This invention relates to a combined type-writing and computing machine of a type in which a series of computing heads are arranged to come into action individually to correspond with certain columns of the work sheet on the typewriter carriage, and in which when in action, each head receives all of the digits of a number at one stroke of a general operator from a pin set item-registering mechanism.

In the adaptation of this invention here-with shown, separate numeral keys are used for controlling the computing mechanism from those used to print numbers in an ordinary typewriting operation. A special means is used to print the numbers on the work sheet when the machine is used for computing. This means includes a printing register which is connected successively to the several computing heads as they come into action, in such a way that the wheels thereof are rotated amounts corresponding to the digits which are transferred from the pin set item-registering mechanism to the wheels of the active computing head by one stroke of the general operator.

After the digits registered by the pin set mechanism have been transferred to the active computing head and to the printing register, the return movement of the general operator swings the printing register bodily against the platen to print a number on the work sheet carried by the platen. After each printing the printing register is returned and the wheels thereof automatically reset to zero, so that the number printed each time is an item number, and corresponds to the series of keys struck. In other words, the several digits of a number are registered for printing, as well as for computing, and then are run up and printed all at once.

Arrangement is also made whereby the item printing mechanism is shifted out of

the way and out of action when the change is made from one computing head to another, and when the typewriter carriage is jumped from one column to a new column.

The computing heads in this instance are shown to be carried by a rotatable turret with an escapement mechanism enabling an automatic movement to bring the computing heads, successively and in order, into action. Manual means is also provided whereby this turret can be rotated to selectively control the activity of any one of the computing heads. This manual means is shown to carry an indicator whereby the particular computing head in action can be readily ascertained.

Other features and advantages will hereinafter appear.

In the accompanying drawings,

Figure 1 is a vertical section taken from front to rear of the machine.

Fig. 2 is a fragmentary vertical section taken at right angles to the section of Fig. 1, and showing the connections whereby the printing register is actuated to run up the digits run up by the particular computing head in action, and also showing the means for reciprocating the printing register.

Fig. 3 is a top plan view with parts broken away to show the underlying structure.

Fig. 4 is a vertical sectional view, showing a detail of the section arrangement whereby the printing register is reciprocated during a single stroke of the general operator.

Fig. 5 is a horizontal section of certain of the parts shown in Fig. 4.

Fig. 6 is a fragmentary vertical section, showing one of the printing wheels of the printing register and the means whereby the printing wheel is returned to zero after each printing action.

Fig. 7 is a view partly in elevation and partly in section, of the mechanism shown in Fig. 6.

Fig. 8 is an enlarged vertical section, showing the connections for driving the printing register from the active printing head, thrown to an inactive position.

Fig. 9 is a bottom plan view, showing the escapement and detent mechanism for the

spring drum which rotates the turret carrying the series of computing heads.

Fig. 10 is a fragmentary perspective view, showing the escapement dogs for controlling the escapement wheel shown in Fig. 9.

Fig. 11 is a fragmentary rear view in elevation of one of the computing heads.

Fig. 12 is a fragmentary horizontal section, showing the indicating disk for designating which of the computing heads is in action.

Fig. 13 is a skeleton perspective view, showing the connection between the tabulating mechanism and the frame which carries the driving connection between the computing head and the printing register. This view illustrates how the printing mechanism is thrown out of operation while the tabulating mechanism is thrown in action to cause the movement of the typewriter carriage.

Fig. 14 is a side view in elevation partly broken away to show the underlying structure, and showing the printing register thrown up against the platen during the return movement of the general operator.

Numeral keys 1 have stems 2 extending through guide openings in a block 3, and held up by springs 4. These stems project below said block to positions just over a set of computation pins 5 mounted upon rack bars 6, in the manner set forth in the application of Frederick A. Hart, No. 466,836, filed December 10, 1908.

By depressing the keys, there may be depressed or set such pins 5 as correspond to the number which is to be computed. The bars 6 have racks 7, to mesh with idle pinions 8, which mesh with computation gears 9, the latter meshing with gears 10 on dial wheels 11.

After depressing the keys 1, there is operated a handle 12, which is fixed on a rock shaft 13, extending across the machine and having at its ends segments 14 to mesh with pinions 15, the latter meshing with a pair of racks 16, connected by a cross bar 17, the parts from 12 to 17 forming a general operator for the computation racks and gears. When the general operator moves forwardly it carries the cross bar 17 into engagement with such of the pins 5 as have been set up on the rack bars 6, so as to advance the rack bars 6 forwardly, bringing the racks 7 thereon into mesh with the idle pinions 8 to rotate the same and thus transmit a rotation to the dial wheels 11 corresponding to the particular pins 5 set on the accordant rack bars 6.

The computation gears 9 may be provided with tens-carrying trains 19, substantially as set forth in said Hart application; each train comprising a pinion 20, which is engageable by a starting tooth 21 upon com-

putation gear 9; and also comprising a three-toothed pinion 22, to mesh with a ten-toothed gear 23, connected to the next higher computation gear 9.

Each train, after being started by said tooth 21, is actuated by one of a series of spurs 24, carried upon a shaft 25, which makes a revolution once in each return movement of the general operator 12. One of the general operator racks 16 is connected by two gears 26 and 26^a to a pinion 27, which has a clutch connection to the spur-shaft 25 (Fig. 8); said connection comprising a ball 28, seated in a pocket 29 in shaft 25, and pressed by a spring 30 into a recess 31 in the pinion 27, so that said pinion may move idly during the forward stroke of the general operator, but may during the return stroke, turn said shaft a full revolution. The spurs engage such pinions 20 as may have been displaced by the starting teeth 21 on the computing wheels, and complete the operations of the tens-carrying trains. Spring detents 32 and 33 are provided for the gear 23 and the pinion 20, respectively.

Upon the return of the general operator to normal position, the cross-bar 17 engages shoulders 34 upon the computation racks 6, and return the latter to normal positions; and a plate 35 is raised to reset the depressed pins 5, in the manner set forth in said Hart application.

The wheels 8, 9, 10 and 11, with their appointments, are mounted in a casing or support 36, to form a computing head which is shown at Fig. 2 in position for engagement with the racks 7 and the spurs 24, but is shiftable out of such position; being for this purpose mounted upon a carrier or carriage in the form of a revoluble turret 37, which is loosely mounted upon a stationary vertical shaft 38. By revolving this turret, the computing head 36 is moved out of working position at Fig. 1, and another computing head 41 on said turret may be moved into working position. The turret may again be shifted, and the computing head 41 moved out of working position, and another computing head 42 may be moved into working position; and so on, there being preferably five more computing heads, marked from "43" to "47" inclusive, and these computing heads being arranged at equidistant points from the shaft 38 and from one another.

The turret may be revolved by a spring 48 coiled around shaft 38 and contained in a barrel 49, which is fixed to the hub of the turret. Projecting from the bottom of the spring barrel may be a series of eight equidistant teeth or pins 50, to coöperate with escapement dogs 51, 52 mounted on a rocker 53 (Fig. 10), the latter pivoted on the frame-work and connected by an arm 54 and link 55 to a lever 56, so that upon de-

pression of said lever, the dog 51 is permitted to escape, and the spring 48 swings the turret, together with the computing heads thereon, to displace the computing head that has just been actuated, and bring its succeeding computing head to a position to be operated upon by the key-controlled mechanism.

One end of the spring 48 is fixed to shaft 38, which extends from the bottom to the top of the casing 58 of the machine, and has bearings 58^a, 58^b, whereby it may be rotated, for restoring the tension of spring 48.

In order to rewind the spring 48, use is made of the forward stroke of the general operator to put a renewed tension on this spring. For this purpose, there is provided a spring-pressed pawl 59, mounted on a bar 60 on the general operator, which pawl is so arranged that while it will engage the ratchet wheel 61 on the shaft 38 idly during the return stroke of the general operator, it will engage the same effectively during the forward stroke of the general operator, to cause a rewinding of the spring. The ratchet wheel 61, however, is loosely mounted on the shaft 38 but has a slip friction clutch engagement therewith. For this purpose, there is fixed on the shaft 38, a disk 62^a and a collar 185, between which the ratchet 61 is located. The connection between the ratchet 61 and the shaft 38 is yieldingly maintained by one or more spring shims or washers 64, which are interposed between the facing sides of the disk 62^a and the ratchet wheel 61. It will thus be evident that until the spring 48 is completely wound, this arrangement will form a positive enough connection between the ratchet 40 wheel 61 and the shaft 38; but as soon as the spring is completely wound, the connection will admit of slipping, so as to prevent any breakage of the parts.

To prevent the accidental reverse movement of the shaft 38 to unwind the spring 48, there is provided on the shaft, a locking ratchet 63, which is engaged by a spring-pressed detent 62.

Computation may thus be performed upon the computing heads in succession, by the single set of racks forming a single actuating means. It will be understood that the racks are preferably normally out of mesh with the pinions, so as not to interfere with the movement of the turret.

While the lever 56 could be operated successively a number of times to bring any desired computing head into action, this would be slow and for other reasons in this invention, inadvisable. There is therefore provided manual means whereby any computing head desired can be brought into action. For this purpose, the spring barrel 49 is provided with a gear 70 which meshes 65 with a gear 71 on stud shaft 72. The gear

71 is in turn driven by a gear 73 on a vertically extending shaft 74. The upper end of the shaft 74 extends outside the casing 58 to a point convenient to the operator, where it is provided with a crank 75. It will thus 70 be seen that the hand crank 75 can be rotated to rotate the spring barrel 49.

In view of the escapement dogs 51 and 52, however, this rotation must of necessity be in a rearward direction, the dogs remaining 75 inactive, but being jointed, as shown in Fig. 10, so as to admit of a backward rotation of the spring barrel 49. That is to say, the dogs 51 and 52 are each formed in two sections 76 and 77 hinged together and held in 80 normal position by means of a spring 78. The dogs are provided with stop pins 79 which prevent a pivotal movement of the section 77 when approached by the pins 50 in one direction, but admit of a pivotal 85 movement of the section 77 when approached by the pins 50 in the opposite direction.

In order that it may be readily ascertained which computing head is in action, there is provided on the shaft 74 an indicator 80, shown in the form of a disk having on its upper surface numerals from 1 to 8, to correspond to the eight computing heads carried by the turret. These numbers are visible through a sight opening 81 in the 95 casing 58.

Leaving the computing part of the machine for the time being, and considering the typewriting mechanism, it will be seen by reference to Fig. 1, that numeral keys 82 100 and character keys 83 are provided with downwardly extending stems 84, which are pivotally connected to arms 85 on rotatable shafts 86. These shafts extend to the rear of the machine where they are provided 105 with other arms 87 pivotally connected to upstanding links 88. The links 88 in turn are connected to arms 89 on rock shafts 90 which bear at their forward ends, arms 91 connected by means of links 92 to levers 110 93. The levers 93 rock bell cranks 94 to swing type bars 95 up rearwardly against the front side of a platen 96 mounted on a carriage 97. The carriage 97 is provided with the usual Underwood escapement mechanism which consists of a universal frame 98 adapted to be actuated by a heel 99 on each of the type bars 95 when the latter swing upwardly to strike the platen. The universal frame 98 carries a pair of pawls 115 100 which coöperate with an escapement wheel 101 to control the rotation of a pinion 102 which meshes with a rack bar 103 pivotally supported by means of arms 104 carried by the carriage 97.

This escapement mechanism permits a spring barrel 105 to draw the carriage forward step-by-step. In addition to the step-by-step movement, the carriage may have a jump movement as in skipping from one 130

column to another. For this purpose, at the front of the machine there are provided tabulating keys 106 connected by means of stems 107 to arms 108 on rock shafts 109. 5 These rock shafts likewise extend rearwardly, where they are provided with arms 110 which may have a pin and slot connection with vertically extending links 112. These links are connected to rock levers 113 10 which bear at their forward ends against the bottoms of vertical plungers 114. The plungers 114 are moved upwardly when their corresponding keys are operated to project in the path of stops 115 adjustably 15 mounted on a rack 116 carried by the carriage 97.

All of the plungers 114 are provided with notches 117 forming a shelf on which rests a universal lever 118 which is adapted to 20 be rocked when any of the tabulating keys is actuated, so as to pull downwardly on a link 119 whereby an arm 120 is rocked upwardly at its forward end. This arm bears 25 at its forward end a roller 121 resting on the under side of a smooth portion of the rack 103, so as to lift it out of mesh with the pinion 102, so as to enable the carriage to move forward freely under the traction of its spring barrel 105, until one of the stops 115 30 comes into engagement with the plunger 114, which happens to be projected upwardly.

It will be seen by this arrangement that the numeral keys 82 of the typewriting mechanism are not connected to actuate the 35 computing mechanism. It will also be seen that the computing keys 1 are not connected to actuate the printing mechanism of the numeral keys 82. For this reason there is provided in this case a special printing 40 mechanism, whereby when the computing mechanism is operated, the numbers run up in the computing mechanism will be printed on the work sheet carried by the platen 96. For this purpose there is provided in super- 45 posed relation with the active position of the computing heads a driving mechanism or connection 122 whereby a printing register 123 may receive the digits of the number run up in the active computing heads.

50 The connection 122 includes a frame 124 (see Figs. 1, 8 and 13) mounted for vertical movement by means of pin and slot connections 125 and having downwardly extending guiding legs 126 which are adapted to engage 55 with the side plates 36 on the active computing head when in position, to bring in register with the gears 10 thereof accordant gears 127. The gears 127 are loosely mounted on a shaft 128 which is supported 60 by the frame 124. Each of the gears 127 carries for rotation therewith a pinion 129 which meshes with the accordant one of a series of racks 130 carried by the lower ends 65 of levers 131 pivotally mounted on a rod 132 carried by the frame 124. The upper ends

of these rocking levers 131 carry other segment racks 133 which drive the wheels 134 of the printing register 123.

As will be seen by reference to Figs. 6 and 7, each of the wheels 134 comprises a hollow barrel or drum loosely mounted on a fixed shaft 135 secured to a reciprocating frame 136. On each of the wheels 134 there are provided raised types 137 numbered from "0" to "9." These numbers, when the printing register is forced up into engagement with the platen, as shown in Fig. 14, will act as type to print through the usual typewriter ribbon on the work sheet carried by the platen.

Loosely mounted on each of the barrels of each of the printing wheels 134, there is provided a gear 138 which has a one-way pawl and ratchet connection with the barrel of the printing wheel. These gears 138 meshing 85 with the racks 133, form a driving connection between the wheels 134 and the racks for effecting an accumulating rotation of the printing wheels, but permitting a return motion of the racks without actuating the 90 printing wheels.

In order that each printing wheel may return to zero after having printed a digit, there is provided within the barrel thereof, a spiral spring 139 which is connected at one 95 end to a printing wheel, and is secured at its opposite end to the fixed shaft 135.

To hold the printing wheel in any adjusted position before printing, there is provided in each case a detent 140 which is 100 adapted to engage in notches 141 located on the wheel in correspondence with the printing numbers or types 137. This detent is held normally in the juxtaposed notch by means of a spring 142.

The oscillating frame 136 which carries the printing wheels 134 which together form the printing register 123, is slidingly mounted in a guiding frame 143 so that the register can be swung or oscillated from a position 110 such that its wheels mesh with the racks 133 to a position such that the type on the wheels strike against the front side of the platen 96.

The means for oscillating or reciprocating the printing register obtains its motive 115 force from the general operator during the return stroke thereof. For this purpose there is provided, as will be seen by reference to Figs. 1, 4, 5 and 14, a gear 144 mounted loosely on a stud shaft 145, and 120 meshing with one of the racks of the general operator. Also loosely mounted on the shaft 145 there is provided a mutilated bevel gear 146 which is rotated by the gear 144 during the return stroke of the general 125 operator. For this purpose the gear 146 is provided with a socket 147 having a cam bottom 148. Within this socket or pocket 147 there is provided a roller or ball 149 which rests against a spring 150 in such a manner 130

that the spring tends normally to force the ball out into the narrow portion of the pocket 147, so as to form a clutch connecting the gear 144 with the gear 146. This clutch arrangement is formed on a hub portion of the gear 146 which extends into an annular groove of the gear 144. During the initial stroke, however, of the general operator, the rack 16 rotates the gear 144 (see Fig. 4) in a clockwise direction, so that the roller 149 is forced inwardly against the tension of spring 150 into the larger portion of the pocket 147, so that there is no clutch connection between the gear 144 and the gear 146, whereby the gear 146 remains stationary.

During the return motion, however, of the general operator, the gear 146 is rotated by the gear 144, so that the bevel segment thereof comes first into engagement with a bevel gear 151 and then in engagement with a bevel gear 152, both of which are secured to a shaft 153. By this engagement, the shaft 153 is given first a rotation in one direction and then a rotation in the other direction. The upper end of the shaft 153 is provided with a bevel gear 154 meshing with a bevel gear 155 having secured for rotation therewith a gear 156. The gear 156 is arranged to mesh with a gear 157 (see Fig. 2) secured on a shaft 158, which is slidably and pivotally mounted in a stationary frame 159, and rotatably mounted in the frame 124, so that it can move with the frame 124 to move the gear 157 into and out of mesh with the gear 156.

The shaft 158 is also provided with a pair of gears 160, which mesh with a pair of arcuate racks 161 carried by the reciprocating frame 136, which carries the printing register 123.

It will be seen that the return stroke of the general operator through the connecting gearing swings the printing register up to the position shown in Fig. 14, and then back again to the position shown in Fig. 1. During the return stroke, the detents 140 are released to enable the springs 139 to return the printing wheels to zero. For this purpose, each of the detents 140 is provided with a trip 162, which engages with a fixed bar 163 on the frame of the machine. These trips 162 are pivotally mounted on the detents and held by springs, so that they will yield ineffectively during the upstroke of the printing register 123, and will form a rigid intermediary during the downstroke of the printing register, causing the detents 140 to be drawn out of the sockets 141.

When the shift is made from one computing head to another, it is advisable at the same time to shift the typewriter carriage 97 so as to bring a fresh column of the work sheet in opposition to the printing point. To do this, the link 55 extends

downwardly beyond the arm 54 to a point where it connects with an arm 164 on a rock shaft 165. Rock shaft 165 extends to the rear of the machine, where it is provided with an arm 166 having a pin and slot connection with the downward extension of one of the links 112.

It will be seen that when the lever 56 is actuated, one of the plunger bars 114 will be lifted in the same manner as if the corresponding tabulating key was actuated, thus attaining a jump movement of the carriage 97. It will readily be seen that when the computing heads are changing, and when the carriage is moving, it would be inadvisable to have the gearing connecting the computing head with the registering mechanism in co-operation with the computing head, and also it would be inadvisable to have the drive from the general operator to the reciprocating mechanism for the register complete.

Lever 56, as will be seen by reference to Fig. 13, is in reality duplex, both parts, which move in unison, having portions extending beyond the pivot point to underlie pins 167 on the frame 124. As has been said above, the frame 124 has a pin and slot mounting 125, so that it is free to move upwardly when the lever 56 is depressed, thereby carrying the gears 127 out of mesh with the gears 10, and also lifting the gear 157 out of mesh with the gear 156. When this occurs, the computing head in action can be readily replaced by another computing head, and there is no danger of the printing register 123 being brought in contact with the platen while the platen is traveling with the carriage.

In the use of the device, one of the computing heads is brought in register with the rack bars, so as to be actuated thereby to register the proper numbers. The keys 1 are then struck, so as to set the accordant pins on the rack bars until the number which it is desired to compute has been registered by the setting of the pins on the rack bars. The general operator is then moved forwardly by an actuation of the crank 12, so that the registered number is transferred to the computing head which happens to be in action. This computing head, in turn, transfers the several digits of this number to the printing register 123, through the intermediary of the connected gears and segment racks. The pawls 140 catch the printing wheels and hold them in their adjusted positions against the tension of springs 139.

During the forward motion of the general operator, the raising mechanism for the printing register has no effect, because the clutch connection is inactive. During the return motion of the general operator, however, the clutch connects the bevel gear 146 in driven relation with the gear 144, so that

it is rotated one complete revolution. During the first half of a revolution, it rotates the shaft 153 in such a direction as to drive the rack bars 161 upwardly, until the printing register comes into the position shown in Fig. 14 with the raised type thereon in engagement with the ribbon of the type-writing mechanism, so that the number which has been registered by the computing mechanism will be printed on the work sheet. This number is the item number, and not the total which will appear on the dial wheels 11 if several numbers have been previously run up on the active computing head. During the second half of the rotation of the gear 146, the gear portion thereof will drive the shaft 153 in the opposite direction, causing the racks to be drawn down, thus returning the printing register 123 to its normal position, with the computing wheels thereof in mesh with the racks 133.

On returning, the trips 162 will hit the bar 163 releasing the dogs or detents 140, permitting the springs 139 to return the printing wheels 134 to their normal zero position.

The gears 138 then come in mesh with the racks 133, when the general operator has completely returned to its normal inactive position. At this time, the change from one computing head to another is made by pressing downwardly on the lever 56. Lever 56 rocks the dogs 51 and 52 to permit the spring barrel 49 to rotate, whereby the turrets 37 will be rotated, bringing the next computing head in active relation with the rack bars 7, and also beneath the driving connecting mechanism to the printing register 123. When the lever 56 was depressed, however, it also rocked the shaft 166 which actuated one of the plungers 114 to enable a jump movement of the carriage 97 to the next column. Before either of these movements takes place, however, the lever 56 raised the frame 124 and brought the gears 157 and 127 out of mesh respectively with the gears 156 and 10, a lost motion pin and slot connection being provided between the lever 56 and the link 55, to permit this to occur before the release of the carriage and the turret.

As soon as the gears 127 are moved out of mesh with the gears 10, the springs 180 will return the rocking levers 131 to their normal position, which movement is permitted by the pawl and ratchet connection of the gears 138 with the printing wheels 134.

When the new computing head is in position, the same operation can be repeated, the computing head adding the new number and at the same time transmitting the number as an item to the printing register for it to transfer to the work sheet on the platen. This operation may be repeated over and

over again, each computing head adding a separate column of numbers, and the numbers being transferred to the work sheet by the printing register.

Variations may be resorted to within the scope of the invention, and portions of the improvements may be used without others.

Having thus described my invention, I claim:

1. The combination with a plurality of numeral keys, of a series of computing heads, means for bringing said computing heads individually subservient to control by said numeral keys, a printing register, and means for driving said printing register from the active computing head, so as to run up thereon numbers run up on the active computing head.

2. The combination with a plurality of numeral keys, of a series of computing heads, means for bringing said computing heads individually subservient to control by said numeral keys, a printing register, means for driving said printing register from the active computing head, so as to run up thereon numbers run up on the active computing head, and means for shifting said registers to print.

3. The combination with a plurality of numeral keys, of a series of computing heads, means for bringing said computing heads individually subservient to control by said numeral keys, a printing register, means for driving said printing register from the active computing head, so as to run up thereon numbers run up on the active computing head, means for shifting said register to print, and means for automatically returning said registers to zero after printing.

4. The combination with a plurality of numeral keys, of a series of computing heads, means for bringing said computing heads individually subservient to control by said numeral keys, a printing register, means for connecting said printing register to the active computing head, so as to run up thereon numbers run up on the active computing head, and means for disconnecting said register while changing from one computing head to another.

5. The combination with a computing head for running up and exhibiting numbers, of a printing register for running up numbers to be printed, connections for enabling the concomitant actuation of said computing head and said register equivalent amounts, a general operator for causing the running up of numbers in said computing head and said register, and means actuated by said general operator for reciprocating said register to print.

6. The combination with a series of computing heads, of a single printing register and means for bringing said register into

- individual driving connection with said computing heads so as to be driven thereby to run up on said register numbers run up on said computing heads and means for enabling said register to print. 5
7. The combination with a series of computing heads, of computing mechanism for operating said computing heads, a rotatable turret for carrying said computing heads individually into coöperation with said computing mechanism, an escapement mechanism for controlling the rotation of said turret to bring said computing heads successively and in order into coöperation 10 with said computing mechanism, and manual means for rotating said turret to bring any of said computing heads selectively into coöperation with said computing mechanism. 15
- 20 8. The combination with a carriage having a platen thereon, of a printing register adapted to accumulate a series of digits comprising a number, means for actuating said printing register to print on a work sheet on the platen, means for enabling a feeding movement of said carriage, and mechanism for preventing the printing action of said register during the movement of said carriage.
- 25 9. The combination with a series of computing heads interchangeable to an active position, of a printing register, adapted to have numbers run up on said computing heads transferred thereto, a carriage having a platen thereon, means for manipulating said register to print on a work sheet on said platen, mechanism for enabling a movement of said carriage, mechanism for enabling the movement of said computing 30 heads to change from one to the other, and means for preventing the printing movement of said register while said carriage is moving, and also preventing the transfer of a number from a computing head to said 35 register while said computing heads are moving. 40
10. The combination with a plurality of computing heads, of actuating mechanism for said computing heads, a traveling carriage, tabulating mechanism for affording jump movements of said carriage to bring the same to different computing zones or 45 columns, jump-movement mechanism for bringing different ones of said computing 50 heads into action corresponding to different computing zones or columns, and a single means for concomitantly controlling said tabulating mechanism and said jump-movement mechanism so as to accord the computing zones as determined by said carriage 55 with the computing zones as determined by said computing heads. 60
11. The combination with a plurality of computing heads, of actuating mechanism 65 for said computing heads, jump-movement mechanism for bringing about individual co-operation of said computing heads with said actuating mechanism to afford different computing zones, a traveling carriage, tabulating mechanism for affording jump movements of said carriage to give different computing zones, a finger-piece, and connections between said finger-piece and both said tabulating mechanism and said jump-movement mechanism to afford a concomitant change 70 as determined by said carriage and as determined by said computing heads. 75
12. The combination with a series of computing heads, of actuating mechanism for said computing heads, a jump-movement mechanism for bringing about a relative jump movement between said actuating mechanism and said heads, so as to bring individuals of said heads into play, a traveling carriage, tabulating mechanism for positioning said carriage for different computing zones, and mechanism for concomitantly causing simultaneous actuations of said tabulating mechanism and said jump-movement mechanism so as to concomitantly 80 change the computing zone as determined by said carriage and by said computing heads. 85
13. The combination with a series of computing heads, of actuating mechanism for said computing heads, a carrier movable to bring about the individual effectiveness of said computing heads, an escapement mechanism for said carrier, a traveling carriage movable to different computing zones or 90 columns, an escapement mechanism for said carriage, and a manual control connected to concomitantly actuate both said escapement mechanisms. 95
14. The combination with a rotatable turret, of a series of computing heads mounted on said turret, a single set of actuating mechanism capable of operating a single computing head, motive means for rotating said turret to bring individuals of said computing heads into coöperation with said actuating mechanism, a traveling carriage, motive means for traversing said carriage, controlling means for governing the action of said motive means for said turret, controlling means for governing the action of said motive means for said carriage, and a manual control common to both said controlling means. 105
15. The combination with a rotatable turret, of a series of computing heads on said turret, a single actuating means capable of actuating a single computing head at a time, means for rotating said turret to bring individuals of said computing heads into co-operation with said actuating means, an escapement for controlling the rotation of said turret, a traveling carriage, tabulating mechanism for controlling jump movements of said carriage, a hand lever, and connec- 110 115 120 125 130

tions to both said tabulating mechanism and said escapement mechanism enabling the concomitant actuation of the same to bring about a change in the computing head with 5 a change in the computing zone as determined by said carriage.

16. The combination with a series of computing heads, of actuating means for said computing heads, a jump-movement mechanism for bringing about a relative movement between said actuating means and said computing heads so as to bring individuals of said computing heads into play, a traveling carriage, tabulating mechanism for affording jump movements of said carriage to determine different computing zones or columns, a printing register coöperating with the active computing head to register the items registered therein and coöperating with 10 said carriage to print the items registered in said register, and manual means for effecting a concomitant action of said tabulating mechanism and said jump-movement mechanism so as to bring about a relative movement between 15 said actuating means and said computing heads to bring a new computing head into action and also so as to bring about a relative movement between said carriage and said register so as to permit the 20 printing by said register in a new computing zone or column.

17. The combination with a computing mechanism, of a printing register connected to run up items registered in said computing mechanism, a traveling carriage arranged to carry the work-sheet to be printed on by said register and movable to determine different computing zones or columns, devices for causing said carriage to travel, 35 and means for interrupting the connection between said computing mechanism and said register while said carriage has a movement from zone to zone under the control of said devices.

40 18. The combination with a computing mechanism, of a printing register connected to be actuated from said computing mechanism so as to register items run up in said computing mechanism, a traveling carriage arranged to carry a work-sheet to be written on by said printing register and moving to determine different computing zones or columns, devices for causing said carriage to travel, means for advancing said register to 45 print, and mechanism for automatically rendering said advancing means ineffective while said carriage travels under the control of said devices.

46 19. The combination with a computing mechanism including a plurality of computing heads arranged to be brought individually into action, a printing register connectible to register items run up in the active computing head, an item register adapted 55 to carry items into the printing register

through the computing heads, and means for interrupting the connection of said printing register with said computing heads while changing from one computing head to another.

70

20. The combination with a computing head, of a printing register connectible to receive items registered in said computing head and to print the same, a carriage co-operating with said register to print the 75 items on a work-sheet carried by the carriage, said carriage traveling to determine different computing zones or columns, means for interrupting the connection between said register and said computing head at the 80 printing actions of said register, and means for interrupting the connection between said computing head and said register during a traveling movement of said carriage.

75

21. The combination with a computing head, of a printing register connected to be driven from said computing head to register items run up in said computing head and print the same, a traveling carriage co-operating with said printing register to print 90 items on a work-sheet carried by the carriage, said carriage traveling to determine different computing zones or columns, means for advancing said printing register to said carriage to print, means for interrupting the 95 connections between said printing register and said computing head during the movement of said register to print, and means for rendering said advancing means ineffective during a traveling movement of said carriage.

100

22. The combination with a computing head, of a registering mechanism for said computing head, a general operator for co-operating with said registering mechanism 105 to run up numbers in said computing head, a printing register connected to said computing head to be driven therefrom to register numbers to be printed, and means driven by said general operator for advancing said 110 register to print and returning the same subsequent to the running up of a number in said computing head and said register.

105

23. The combination with a computing head, of a computation - registering mechanism for said computing head, a general operator having a back-and-forth stroke arranged to coöperate with said registering mechanism and run up a computation in said computing head, a printing register connected to be driven from said computing head to register items to be printed, and connections for reciprocating said register solely during the return stroke of said general operator and after said printing register and 115 said computing head have registered the items to be printed.

120

24. The combination with a computing mechanism, of a general operator for actuating said computing mechanism, a printing 125

130

register connected to be driven from said computing mechanism so as to register an item to be printed, a rack for advancing said printing register, a gear meshing with said rack, a train of gearing to said gear including a mutilated gear meshing with a pair of oppositely-facing gears to drive said first-mentioned gear alternately in opposite directions, and means for driving said mutilated gear from said general operator.

25. The combination with a plurality of computing heads arranged to be brought individually into action, of a printing register, mechanism connecting the computing head in action with the printing register so that the former will drive the latter, and means for interrupting the connection between said printing register and said computing head while changing from one computing head to another.

26. The combination with a plurality of computing heads arranged to be brought into individual action, of a printing register, mechanism connecting said printing register with the active computing head so that the former may be driven from the latter, and shifting means acting automatically to bring a new computing head into action and move said mechanism out of the range of action of the computing heads while effecting the change between computing heads.

27. The combination with a traveling platen arranged to carry a work-sheet, of a series of registers, means for concomitantly bringing a fresh computing column of the work-sheet to the printing point and a new register into action, and printing means for taking from the register as computed each

number and carrying it up to the accordant column of the work-sheet.

28. The combination with a computing head for running up and exhibiting numbers, of a printing register for running up numbers to be printed, and a train of gearing from the former to the latter so that the latter may be driven from the former, said train of gearing being interruptable at two points, one at said printing register and the other at said computing head.

29. The combination with a platen, of printing means coöperating with said platen, and an exhibiting computing head comprising computing wheels and causing the numbers printed by said printing means to accord with the numerical activity of the wheels of said head.

30. The combination with a printing register, of indexing mechanism connected to drive said register, and a sight register forming an element in the driving connection between said indexing mechanism and said printing register.

31. The combination with a single printing register, of a unitary indexing mechanism connectible to operate said printing register, and a plurality of sight registers, any one of which may form an element in the chain of connection between said indexing mechanism and said printing register, so that the common printing register may transcribe a number run into any one of said sight registers by said indexing mechanism.
